LITTER RECEPTACLE

Leonard M. Yordon, Daytona Beach, Fla., assignor to
Repadco Incorporated, Daytona Beach, Fla.

Continuation-in-part of design application Ser. No.
277,598, Aug. 3, 1972, now Patent No. 231,072.
This application May 18, 1973, Ser. No. 361,647

Term of patent 14 years

Int. Cl. D7—07
U.S. Cl. D7—194

FIG. 1

FIG. 3

FIG. 2

FIG. 1 is a top plan view of the litter receptacle, showing my new design;

FIG. 2 is a front elevational view;

FIG. 3 is a right side elevational view;

FIG. 4 is a top plan view of a litter receptacle showing a modified form of my new design;

FIG. 5 is a front elevational view thereof; and

FIG. 6 is an edge elevational view taken on line 6—6 of FIG. 4.

In either embodiment of my litter receptacle, the bottom is plain and not ornamented.

This is a continuation-in-part of design application Ser. No. 277,598, filed Aug. 3, 1972, now U.S. Pat. No. D-31,072.

I claim:

The ornamental design for a litter receptacle, substantially as shown and described.
